UNITED STATES PATENT OFFICE.

EZRA G. CONE, OF EAST HAMPTON, CONNECTICUT.

DESIGN FOR HAND-BELLS.

Specification forming part of Design No. 6,780, dated July 22, 1873; application filed October 29, 1872.

To all whom it may concern:

Be it known that I, EZRA G. CONE, of East Hampton, in the county of Middlesex and State of Connecticut, have invented a new and original Design for a Hand-Bell, which will be fully understood from the following description, in connection with the accompanying drawing.

A designates the body of the bell, which is provided with a handle, B, of the usual construction, and with a clapper, C, in the usual manner.

My design has reference to the external contour or shape of the body A of the bell, and it will be understood by reference to the drawing, where it will be observed that the metal of the bell is turned off at the mouth of the same so as to form a belt or zone, a, running circumferentially around it, and having a plain or substantially plain surface. From the upper edge of this belt or zone a the metal is curved inward and upward until it reaches the point where the rounding off of the top of a hand-bell usually commences, where I form a second zone, b, also running circumferentially around the bell, and having a plain or substantially plain surface, and presenting

angles more or less sharp at each edge. The inside form of the bell is substantially the same as in ordinary hand-bells.

The zones a b give the bell a neat and attractive appearance; and, more than this, the zone a provides for an increased thickness of metal where the clapper strikes the bell, for improving the tone and preventing breakage at this point; and the zone b becomes a guide in turning the bell, so that the same shall not be turned down so thin at this point as to increase the liability of the top breaking out while ringing the bell.

It is evident that one or both zones a b may be used. My design, therefore, includes the use of one or both of said belts or zones.

What I claim as my invention is:

A design for a hand-bell, A, in which the bell is provided with one or two conical belts or zones, a b, running circumferentially around it, either at the crown or mouth, forming a bevel or bevels bounded by definite angles, substantially as herein shown and described.

EZRA G. CONE.
